LADY'S GARMENT

Application filed May 7, 1929. Serial No. 361,070.

The general use of knickers or the like for ladies is now quite general for certain purposes. Under some circumstances, however, the wearing of knickers is inappropriate and may be embarrassing. The object of the present invention is to provide a garment which shall be convertible readily without removal from the body of the wearer so that the full benefit of knickers may be obtained when desired and yet the protection of a skirt afforded when the exposure of the knickers is not in order. In the preferred embodiment of the invention the garment is of one piece and comprises a pair of knickers or the equivalent of conventional form with which is associated an over-skirt. The skirt is of such construction that it may be drawn up over the body to constitute a blouse thus leaving the knickers exposed. In general appearance the material constituting the skirt is so treated that the skirt itself will be of pleasing appearance but so constructed as to lend itself readily to the conversion, with no inconvenience to the wearer, and without the removal of either the knickers or the skirt. More particularly, the improved garment includes a skirt portion which is so constructed that the skirt is unbroken in contour when in place but which may be provided with openings to receive the arms when the skirt is used as a blouse. Other securing means may be included in the skirt to give it the style and finish of a blouse so that it will readily adapt itself to the body of the wearer.

The construction will be described more fully in connection with the accompanying drawings, in which:

Figure 1 is a view in front elevation showing the improved garment with the skirt portion in place as a blouse.

Figure 2 is a view in side elevation of the garment shown in Figure 1.

Figure 3 is a view in side elevation of the garment shown in Figures 1 and 2 with the skirt portion lowered from the body and in place as a skirt.

The knickers or pants α may be of any material and shape to serve the purpose for which intended. These knickers are secured to a waist at α' by any preferred or convenient

means. The waist is a convertible skirt portion α^2 which is illustrated in Figure 3 as overlying the knickers α , shown in dotted lines. When this skirt portion is thus positioned the knickers are not observable and the wearer appears in conventional skirt attire. When it is desired to have such freedom of action as knickers afford the skirt portion α^2 can be drawn up and secured over the body as illustrated in Figures 1 and 2 so as to constitute a blouse and expose the knickers. It is desired, in accordance with the invention to accomplish this conversion in a way which will be wholly convenient to the wearer and without requiring the removal of the knickers or the skirt. In other words, it is desired to so design the skirt as to enable it to be drawn directly upwardly and secured in place over the body. Different details of construction will suggest themselves to one skilled in the art for accomplishing this conversion in the manner indicated. As shown in the drawings the skirt portion is split down the front and when the skirt is in place these portions are secured together by buttons b which may or may not be exposed to view depending on their arrangement and relationship to the material. In the illustrated embodiment they are not exposed to view when the skirt is in place but are exposed when the skirt portion is drawn up to form a blouse. In such a case some of the buttons at the neck edge may be left unbuttoned to form lapels α^3 of pleasing appearance. Further, the lower open end of the skirt may be closed to some extent when it is drawn up as a blouse by a series of buttons c, d , at opposite sides overlying the shoulders when the blouse is worn. In such an arrangement an ample neck opening is left. Additional buttons e engage the cooperating buttonholes engaged by the buttons c and d , thus closing the slits when the skirt portion functions normally in such capacity. In addition to the opening down the front the skirt portion is also formed with openings α^4 at opposite sides which may be of any desired length for the purpose to be described. As shown in Figure 3 such openings are continuations of the openings closed by the buttons e and itself can be closed when

the skirt is in use by means of hookless fasteners or other securing means such as snap fasteners or buttons. When the openings a^4 are opened wide by disengagement of the fastening means therefor, the skirt portion can be drawn up over the body and the arms inserted through the opposite side openings a^4 . The extent of these openings can be regulated by the securing devices to accommodate the particular wearer.

From the description given it will be understood that there is here embodied in a single garment complete adaptability for the two conditions of use and the style and appearance of each garment, considered ensemble, fully retained. The material of the different sections and the color schemes can be worked out harmoniously and, if desired, the inner and outer portions of the skirt may present different effects so that some variation is displayed depending on whether the skirt is in use or is converted into a blouse. The ease with which the conversion can be accomplished under any circumstances further enhances the adaptability of the garment for different conditions since the wearer can, without requiring privacy, quickly drop the skirt in place to draw it up over the body to give the blouse effect.

Changes in details which do not affect the principle involved will suggest themselves to skilled designers but all such changes are to be deemed within the scope of the appended claims.

What we claim is:

1. A lady's garment comprising knickers, an over-skirt united therewith and having openings at the opposite sides thereof, said skirt being formed with portions adapted to fit the shoulders of the wearer whereby the same is adapted for use as a blouse when drawn up over the body, said openings constituting arm-holes for the blouse and means to close the arm-holes to any desired extent.
2. A lady's garment comprising knickers, a skirt portion united therewith and split down the front and having openings at opposite sides, said skirt being adapted to be drawn up over the body to constitute a blouse, means to secure the front opening more or less for the blouse and independent means to close said side openings for the skirt.

This specification signed this 27th day of April, A. D. 1929.
